PAPER MANUFACTURE

Roland A. Packard, Lee, Mass., assignor to Smith
Paper, Inc., Lee, Mass., a corporation of Dela-
ware

Application January 2, 1935, Serial No. 115

20 Claims. (Cl. 92—20)

This invention relates to the manufacture of paper, and more particularly to the treatment of half stock, especially rag half stock.

In accordance with prior practice, bleached 5 unbeaten rag stock or rag half stock is dropped into a drainer which ordinarily takes the form of a bin having perforated brick at the bottom. After the stock remains in the drainer for a con- 10 siderable period, it must be dug out manually and conveyed to the beater. The drainage is not thorough, and retained bleaching agent has a weakening effect on the fibre.

The object of my invention is to generally im- 15 prove the handling and drainage of rag half stock, that is, unbeaten rag stock, and to avoid the delay and labor heretofore necessary, as well as to improve the strength of the product by thor- 20ough drainage.

To the accomplishment of the foregoing gen- 25 eral objects and numerous more specific objects which will hereinafter appear, my invention consists in the method steps and apparatus elements and their relation one to the other, as are herein- 30 after more particularly described in the speci- 35 fication and sought to be defined in the claims. The specification is accompanied by drawings in which:

Fig. 1 is a side elevation of apparatus embody- 30 ing features of my invention;

Fig. 2 is a plan view of the same;

Fig. 3 is a detail of the table lowering mechanism;

Fig. 4 is a section taken in elevation through the screen or wringer apparatus;

Fig. 5 is a section taken in the plane of the line 5—5 of Fig. 4; and

Fig. 6 is a section taken in the plane of the line 6—6 of Fig. 4.

Referring to the drawing and more particu- 40 larly to Figs. 1 and 2, the complete apparatus comprises a bleacher B, a centrifugal pump P for delivering the stock to a spout S located over the moving screen of drainage and mat-forming apparatus W which, for convenience, may be re- 45 ferred to as a wringer. The rate of feed of stock to the wringer is controlled by bleeding a part of the stock back into the bleacher B, as by the use of overflow sluices O. From another view- 50 point, it may be said that the bleached stock is continuously circulated by the pump P, and that a desired amount of the circulating stock is sup- 55 plied by spout S to the wringer W. The stock is formed into a mat or web by the wringer, and this is piled or lapped on a suitable table T by means of an apron A.

Considering the arrangement in greater de- 5 tail, the bleacher B may be of conventional type comprising a tank 12 provided with a paddle 14 mounted on a shaft 16 driven by appropriate means not shown in the drawings. Tank 12 is 10 provided with a central wall or partition 18 which insures thorough circulation of the stock upon rotation of paddle 14. The contents of the tank are drained through pipe 20 the upper end of which may be stopped by an appropriate valve or 15 cover plate 22. It will be understood that with the cover plate in place, the stock may be treated in the paddle bleacher until properly bleached, at which time the cover plate is removed by a suit- 20 able hook.

In accordance with prior practice, the bleached 25 rag half stock is drained in this manner directly into simple drainage bins from which the stock must later be dug out. I have discovered that it is possible to handle the rag half stock by 30 flowing the same in its liquid or bleaching vehicle, even at a consistency of, say, 4% (4 pounds of dry stock to 96 pounds of water). This was heretofore thought impossible because unbeaten 35 rag stock or rag half stock is heavy, long-fibered, 40 stringy, and easily tangled and snarled. Despite the difficult nature of the material, I find it pos- 45 sible to elevate the same by means of a suitable centrifugal pump 24 which is preferably provided with Stellite cutting blades cooperating with the 50 impeller blades of the pump, and which is further provided at its inlet end with a screw conveyor or feed 26.

The stock ascends through conduit 28 having a 55 horizontal section 30 extending over the bleacher 35 B and terminating at spout S located directly above the end of wringer W. It should be noted that the spout is large, fully open, and preferably expanded or "bell-mouthed". Also, that conduit 28, 30 is preferably devoid of fittings or obstruc- 40 tions which might discriminate between the li- 45 quid and solid parts of the stock. I have accord- 50 ingly devised special means for controlling the rate of flow of stock to the wringer, it being unde- 55 sirable to use ordinary valve or gate means which tend to dam the solid parts of the stock. Instead of obstructing the flow of material, I bleed a part of the flow back into the bleacher B and control the feed to the wringer by modifying the amount of stock bled back to the bleacher. For this pur- 60 pose, I provide overflow sluices O, best shown in Figs. 1, 2, and 6 of the drawings. The conduit 30 is cut away at 32. Troughs 34 are secured to the sides of conduit 30 far below the top of the conduit and preferably near the bottom thereof, and said 65

troughs lead rearwardly and downwardly to a point over the bin B. The forward ends of troughs 34 are preferably closed by a wall or partition 36. It is possible to pivot the troughs 34, thereby regulating the overflow by changing the tilt or angle of the troughs, but I find that satisfactory results are obtainable while fixing the troughs rigidly to the conduit in the manner shown, the feed being regulated by varying the height of the mouth of discharge spout S above the wire screen of the wringer W. For this purpose, the conduit is counter-balanced by weight 38 connected to the conduit by means of an appropriate cord 40 passing over pulleys 42. The position of the conduit 10 may be adjusted by a screw 44 threaded in block 46 mounted on the frame of wringer W. The movement of the spout is small and is accommodated by elasticity of the conduit leading to the spout.

20 Spout S terminates in a large open and preferably expanded mouth 48 the bottom edge of which is disposed parallel to the wire screen 50 of wringer W, as is best shown in Fig. 4 of the drawings. It will be understood that much of the stock flowing through conduit 30 is at a level higher than the overflow troughs, and is simply circulated, with the stock kept constantly in motion to prevent settling and accumulation, and that the part of the stock flowing from spout S spreads out on the traveling screen. The stock is at all times kept in motion or dynamic, and is not allowed to dwell or become static, for it then promptly settles. There is an automatic regulation of the rate of feed because the stock builds up on the wire at the 30 spout and automatically checks the feed of stock when the supply is excessive. This, of course, encourages overflow at the sluices and increased bleeding of stock back into the bleacher. In practice it is seldom necessary to change the position 35 or adjustment of the spout. It will be evident, however, that the elevation of the spout above the screen determines the thickness of the mat of material deposited on the screen before the checking or automatic regulation takes effect.

40 This in turn is a measure of the rate of feed of stock to the wringer.

45 The wringer W comprises a frame 52 mounted on posts 54 and supporting at one end a breast roll 56 and at the other end a couch roll 58. The wire screen 50 is in the form of an endless band passing around the breast roll 56 and couch roll 58. It will be noted that the couch roll 58 is at a higher elevation than breast roll 56, so that the screen is given a slight upward inclination. The upper or useful part of the screen is supported on a large number of closely adjacent carrier rolls 60 and also upon maple boards 62 and 64, as is best shown in Fig. 4. The screen may be four feet or more in width and is preferably of fine 55 mesh, say 40 x 40. The lower part of the screen is supported on idlers 66, while the screen is kept taut by a tensioning roll 68.

Above the screen, I provide a series of rolls spaced progressively nearer the screen for compressing the stock into a mat or web and for wringing substantially all of the wash water out of the same. In the present example, I employ first and second rolls 70 and 72 which act primarily as forming rolls to level and form the stock 60 into a relatively thick mat. I also provide rolls 74 and 76 which act as press rolls to compress the mat and to eliminate most of the liquid. The wringer terminates with a preferably rubber covered couch roll 78 which bears against couch roll 75 78. The upper couch roll is made extra-heavy

and operates to wring any remaining free liquid from the mat or web of stock. I do not mean that the stock is absolutely dry, but it is nearly dry and much more effectively so than was the case when using drainage bins as in the prior art. 5

It should be noted that the rolls are mounted on arms 80 (see Fig. 1) pivoted at 82 and provided with stop bolts 84 for limiting the permissible downward movement of the rolls. Stop bolts 84 are threaded in arms 80 and are provided with 10 lock nuts 86 to hold the same at any desired adjustment. The adjustment is made such that there is a space of, say, one inch or more between the first roll and the screen, which is reduced, however, to a matter of only, say, one-sixteenth 15 of an inch at the last roll. The mass of the rolls is relied upon for downward pressure, there being nothing to positively prevent upward movement of the rolls.

The reaction of the forming rolls 70 and 72 is 20 taken by the maple boards 62 and 64 which are provided with lateral grooves 88 and drain holes 90 to insure free discharge of liquid. The reaction of press rolls 74 and 76 is taken by the continuous series of carrier rolls heretofore referred 25 to, while the reaction of the final pressure roller 78 is, of course, taken by couch roll 58. The upper rolls are all provided with appropriate doctor means to prevent any stock clinging to the roll from traveling up around the roll. For this purpose, the rolls 70, 72, 74, and 76, which may be made of brass, are fitted with doctor blades 92 preferably made of bakelite. The rubber covered roll 78 is provided with a flapper 94 having rubber blades 96 and rotated against the roll by means of 30 a chain and sprocket drive 98.

The stock is confined to the screen at the side edges of the screen by deckle boards 100, best shown in Figs. 4 and 5, and an end board 101 located at the breast roll. These deckle boards 40 are preferably fitted with rubber deckle strips 102 which bear directly against the screen 50. The rubber strips may be terminated before the end, say, between the press rolls 74 and 76 because from that point on, the mat is already 45 fairly solid and controllable. The wash water expressed from the stock is caught by an appropriate save-all pan 104 which is preferably made co-extensive with the screen. Because of the inclination of the screen and the corresponding 50 inclination of the save-all pan, the liquid drains toward the inlet end of the wringer where it may be discharged at one side by an outlet 106. The floor beneath the wringer is preferably walled-in by curbs 108, and the enclosed space is provided 55 with a suitable drain 110.

The wringer W strengthens the fibre because it greatly shortens the drainage time, and more importantly, because it provides thorough drainage of the bleaching agent. The screen alone, with 60 the stock spread well out on its surface, is a good drainage medium, while the rolls afford a positive compression and wringing of the stock. The absence of a breast box, reservoir or pond, is important because of the stringy tangled condition of the rag half stock, and the impossibility of suspending the same, the stock being in gobs or clumps like handfuls of machinists' waste. The screen is upwardly inclined to help retard the stock and to thereby form a better mat. The 65 mat formation is convenient for transfer to the beater, and wholly eliminates tedious manual digging out of stock from a pit or bin.

The wringer is driven by a motor 112 connected through a speed reducing gear box 114 to the 75

shaft 116 of couch roll 58, which, of course, drives the screen 50. Shaft 116 is provided with a gear 118 which meshes through a direction reversing idler 120 with a gear 122 for driving the apron 5 A, the operation of which will be described in detail later. With respect to the wringer W, the gear 118 meshes with a direction reversing idler 124, which is connected to press roll 76 by a chain and sprocket connection 126. Similarly, rolls 14, 10 72, and 70 are connected by chain and sprocket connections 128, 130, and 132. The linear speed of the wire may be varied, but I find a speed of 140 feet per minute to be satisfactory. I also find it helpful to so gear the earlier rolls, preferably the 15 rolls 70, 72, and 74, that they run at a surface speed slightly greater than the speed of the wire.

The mat or web leaving the wringer is ready to be delivered to a beater. A convenient and preferred way to handle the web is to load the same 20 in lapped formation on a loading table. Referring to Figs. 1, 2, and 3, I provide a loading table T on which the stock is lapped by a loading apron A. Apron A may be made of fabric and passes over drive roll 140 which moves at 25 the same surface speed as the screen 50 and is geared to the couch roll of screen 50 to insure synchronous operation. As previously mentioned, this gearing comprises gear 118, idler 120, and a gear 122 mounted on the shaft of drive roll 140. 30 The apron passes over a carrier roll 142 and then between twin guide rolls 144 mounted on a carriage 146 which is horizontally reciprocable on rails 148. The apron is led back over carrier roll 150, and slack of the apron is preferably taken up 35 by weighted tensioning rolls 152 located on opposite sides of a support roll 154.

Carriage 146 is reciprocated by a motor 160 connected through reduction gear box 162 to a shaft 164 coupled by gears 164' and 166 to crank shaft 168 having at opposite ends the crank discs 170. The crank pins are connected through links 172 to the lower ends of levers 174. These levers are pivoted at 176 and are connected at their upper ends to carriage 146 by means of links 178. It will be understood that reciprocation of the carriage 146 over table T will cause the mat or web of stock supported on apron A to be deposited on the table in lapped formation, as shown in Fig. 1 of the drawings.

Although I have indicated the use of a separate motor 160, it will be understood that this mechanism may, if desired, be operated from motor 112, as by extending the shaft of the motor from gear box 114 to gear box 162. In fact, the 55 use of a single motor is preferable for maintaining exact synchronism between the linear speed of the web and the speed at which the apron guide 146 is reciprocated.

Table T is preferably made vertically reciprocable in order to maintain the top of the stock at a substantially constant level. For this purpose, I mount table T on supports 180 threaded on posts 182 which are geared for simultaneous rotation by a chain and sprocket system 184. 60 One of the posts is provided with a worm gear 186 meshing with a worm 188 mounted on a shaft 190. Shaft 190 carries a ratchet wheel 192 best shown in Fig. 3. The ratchet wheel is operated by a pawl 194 carried by an arm 196 oscillated by a link 198 connected to the crank pin of crank disc 170. The rate at which the table is lowered 65 may be regulated by adjusting the point of connection of link 198 and pawl arm 196, this adjustable connection being indicated at 200. The outer end of shaft 190 is also preferably pro-

vided with a manually operable crank 202. This crank facilitates restoration of the table to elevated position, the pawl 194 being released while the crank is operated.

The operation of the apparatus may be summarized as follows. The stock, which is unbeaten rag stock, is preliminarily bleached in paddle bleacher B. The cover plate 22 is then removed, and the bleached stock is mechanically pumped directly from the bleacher to the moving screen 10 50 of the wringer W. The supply of stock is regulated by bleeding or bypassing part of the stock directly back to the bleacher. The resulting continuous circulation of the stock helps maintain the same in an active condition and at a uniform 15 consistency. No breast box is employed, and every effort is made to prevent damming or dwelling of the stock, with consequent settling of the solid matter. The large open-mouthed spout S and overflow O form a combination practically automatic in operation. The stock is impelled outwardly from the spout and floods out on the wire screen and undergoes preliminary 20 drainage through the screen. It is restrained at the edges by the deckle boards 100. Former rolls 70 and 72 level off the stock and cause additional drainage. Press rolls 74 and 76 compress and further drain the stock to form a compacted mat. This is given a final wringing between couch roll 58 and rubber covered pressure roll 78. 30 The discharged web of material is fed upon and supported by apron A the discharge point of which is reciprocated over table T by carriage 146. This causes a lapping of the web on table T. The table is lowered as stock is loaded thereon, by 35 rotation of the supporting screws 182.

It is believed that the mode of practicing my invention, as well as the many advantages thereof, will be apparent from the foregoing detailed description. It will also be apparent that while 40 I have shown and described my invention in preferred form, many changes and modifications may be made without departing from the spirit of the invention, defined in the following claims.

I claim:

1. In the manufacture of paper, the method which includes bleaching rag half stock, feeding the bleached stock to moving wringer means, and bleeding or bypassing a part of the stock being fed to the wringer means in order to regulate the 50 rate of flow of stock thereto, the stock being handled in a continuous active state of movement, and being given no opportunity to dwell and settle.

2. In the manufacture of paper, the method which includes bleaching rag half stock in a conventional paddle bleacher, feeding the stock to a pump, thereby pumping the stock to wringer means located at an elevation higher than the paddle bleacher, and without damming the stock 60 being pumped to the wringer means bleeding a part of the same back into the paddle bleacher in order to regulate the rate of flow of stock to the wringer means.

3. In the manufacture of paper, the method which includes bleaching rag half stock, feeding the stock in its bleaching vehicle and in a dynamic condition to a traveling screen, bleeding a part of the feed in order to regulate the rate of flow of stock to the screen, and pressing the 70 stock on the screen.

4. In the manufacture of paper, the method which includes bleaching unbeaten rag half stock in a bleacher, feeding the unbeaten stock to a pump and thereby elevating the stock to a travel-

ing screen located higher than the bleacher, bleeding a part of the unbeaten stock being pumped to the screen back into the bleacher in order to regulate the rate of flow of stock to the screen, and pressing the unbeaten stock on the screen.

5. Apparatus for treating unbeaten rag half stock, comprising a bleacher and a centrifugal pump connected to form a circulating system for 10 continuously circulating the unbeaten stock, wringer means, and means to feed a desired part only of the circulating unbeaten stock to said wringer means.

6. Apparatus for treating unbeaten rag half stock, comprising a paddle bleacher and a pump 15 connected to form a closed circulating system for continuously circulating the unbeaten stock, means to feed a desired part of the circulating unbeaten stock to a traveling drainage and 20 wringer screen, and cooperating rolls for pressing the unbeaten stock on the screen and forming the same into a mat.

7. Apparatus for treating unbeaten rag half stock, comprising a bleacher and a centrifugal 25 pump connected to form a closed circulating system for continuously circulating the unbeaten stock, means to feed a desired part only of the circulating unbeaten stock to a traveling drainage and wringer screen, cooperating rolls for 30 wringing and forming the unbeaten stock into a mat, and means at the end of the wringer screen for piling the unbeaten stock in lapped formation on a suitable table.

8. Apparatus for drying bleached rag half 35 stock, said apparatus comprising a frame, a breast roll at one end of said frame, a couch roll at the other end of said frame and higher than said breast roll, an endless wire screen passing around said breast roll and couch roll, a plurality 40 of carrier rolls located beneath and supporting said screen, a plurality of rolls located above and spaced along said screen, a roll located above the aforesaid couch roll, the rolls being arranged successively progressively nearer the screen, means 45 driving some of said rolls, and doctor means for said rolls.

9. Apparatus for drying bleached rag half stock, said apparatus comprising a frame, a breast roll at one end of said frame, a couch roll 50 at the other end of said frame and higher than said breast roll, an endless wire screen passing around said breast roll and couch roll, a plurality of carrier rolls located beneath and supporting said screen, a plurality of forming rolls spaced 55 along said screen, drain boards located beneath the screen at said forming rolls, a plurality of press rolls following said forming rolls, a rubber covered pressure roll located above the aforesaid couch roll, said rolls being arranged successively 60 progressively nearer the screen, means driving at least some of said rolls, said means being arranged to drive the first rolls at a speed somewhat greater than the speed of the screen, and doctor means for said rolls.

10. Apparatus for treating unbeaten rag half stock, said apparatus comprising a bleacher, a wringer, means to feed the unbeaten stock from the bleacher to the wringer, and means to bleed away part of the stock being fed to the wringer 70 in order to regulate the rate of feed of stock reaching the wringer.

11. Apparatus for treating rag half stock, said apparatus comprising a bleacher, a traveling drainage and wringer screen, means to feed the stock from the bleacher and to flow the same on

the screen, a bypass path for bleeding away part of the stock being fed from the bleacher in order to regulate the rate of feed of stock reaching the screen, and means to automatically vary the bleeding of stock in response to variation in the 5 quantity of stock on the screen.

12. Apparatus for treating unbeaten rag half stock, said apparatus comprising a bleacher, a centrifugal pump connected thereto, a traveling wire wringer screen located at an elevation higher than said bleacher, a conduit extending from the pump outlet directly to the screen without intermediate breast box or the like, said conduit being provided with means to bleed excess stock back into the bleacher and thence to the pump, 15 in order to regulate the rate of feed of stock to the screen.

13. Apparatus for treating unbeaten rag half stock, said apparatus comprising a bleacher, a centrifugal pump connected thereto, a traveling 20 wringer screen located at an elevation higher than said bleacher, a conduit extending from the pump outlet to a spout located above the screen, overflow sluiceways located directly in the conduit and leading back to the bleacher, and means 25 to vary the bleeding effect of the overflow sluiceways.

14. Apparatus for treating unbeaten rag half stock, said apparatus comprising a bleacher, a centrifugal pump located therebeneath, a traveling 30 wringer screen located at an elevation higher than said bleacher, a valved conduit connecting the bleacher and the pump inlet, another conduit extending from the pump outlet to a spout located above the screen, said spout being 35 provided with overflow sluiceways extending to a point over the bleacher, and means to adjust the height of the spout above the screen in order to regulate the rate of feed of stock to the screen, the excess stock being returned to the bleacher 40 and thence to the pump.

15. Apparatus for drying bleached half stock, said apparatus comprising a wringer screen to form the stock into a mat or web, and means to pile said mat, said means comprising laterally 45 reciprocable guide means for the mat leaving the screen, a vertically movable table located beneath said guide means, and means for reciprocating the guide means and for simultaneously lowering the table.

16. Apparatus for drying bleached rag half stock, said apparatus comprising a wringer screen to form the stock into a mat or web, and means to pile said mat, said means comprising an endless conveyor or apron, a drive roll for 55 moving the same, a vertically movable table located beneath said apron, guide rolls mounted on a laterally reciprocable carriage for reciprocating the discharge end of the apron over the table, means for taking up the slack of the apron, and means for reciprocating the guide rolls and for simultaneously lowering the table.

17. Apparatus for treating unbeaten rag half stock, said apparatus comprising a bleacher, a traveling wire wringer screen located at an elevation higher than said bleacher, a pump connected to said bleacher and having a discharge conduit extending upwardly to a point directly over the receiving end of the wire screen without intermediate breast box or the like, the discharge end of said conduit being provided with a downwardly directed expanded or bell-mouthed spout the edge of which is disposed generally parallel to the surface of the screen and at a 70 75

height thereabove such as to help regulate the discharge of the stock onto the screen.

18. Apparatus for drying bleached but un-beaten rag stock, said apparatus comprising an endless wire drainage screen, a plurality of rolls for supporting and moving said screen, one or more rolls for pressing stock flowed onto said screen, and means including an enclosed supply conduit having a downwardly turned spout for so flowing the unbeaten stock directly onto the drainage screen as to initially spread and distribute the stock over the surface of the screen, said spout being an enclosed conduit forming a continuation of the supply conduit and having at its bottom end a fully open downwardly directed mouth of large area, said mouth being as large as the cross-section of the conduit and opening directly onto the top of the screen, without intermediate box or the like, the periphery or lip of said open mouth being disposed directly over and generally parallel to the screen, and sufficiently close thereto as to cause the unbeaten stock to spread out sidewardly from the spout over the surface of the screen.

19. Apparatus for drying bleached but un-beaten rag stock, said apparatus comprising a breast roll, a couch roll, an endless wire screen passing around said breast roll and couch roll, a pressure roll located above said couch roll, other pressure rolls above said screen between the couch roll and the breast roll, means driving at least some of said rolls, said means being so arranged as to drive the first pressure rolls at a speed higher than the last pressure rolls, and means to feed the stock in an active dynamic unsettled condition directly onto the screen, said means including an enclosed supply conduit having a downwardly turned spout for so flowing the unbeaten stock directly onto the drainage screen as to initially spread and distribute the stock over the surface of the screen, said spout being an enclosed conduit forming a continuation of the supply conduit and having at its bottom end a fully open downwardly directed mouth of large

area, said mouth being as large as the cross-section of the conduit and opening directly onto the top of the screen, without intermediate box or the like, the periphery or lip of said open mouth being disposed directly over and generally parallel to the screen, and sufficiently close thereto as to cause the unbeaten stock to spread out sidewardly from the spout over the surface of the screen.

20. Apparatus for drying bleached but un-beaten rag stock, said apparatus comprising a frame, a breast roll at one end of said frame, a couch roll at the other end of said frame, an endless wire screen passing around said breast roll and couch roll, a plurality of carrier rolls located beneath and supporting said screen without appreciably obstructing free flow of liquid therethrough, a substantial number of rolls located above and spaced along said screen, means to limit the movement of said rolls away from said screen to amounts which are successively progressively less, whereby the rolls are progressively nearer the screen and have a progressive wringing action, means driving one or more of the rolls, and means to flow the unbeaten stock directly onto the drainage screen, said means including an enclosed supply conduit having a downwardly turned spout for so flowing the unbeaten stock directly onto the drainage screen as to initially spread and distribute the stock over the surface of the screen, said spout being an enclosed conduit forming a continuation of the supply conduit and having at its bottom end a fully open downwardly directed mouth of large area, said mouth being as large as the cross-section of the conduit and opening directly onto the top of the screen, without intermediate box or the like, the periphery or lip of said open mouth being disposed directly over and generally parallel to the screen, and sufficiently close thereto as to cause the unbeaten stock to spread out sidewardly from the spout over the surface of the screen.

ROLAND A. PACKARD.
